CLAIM

The ornamental design for a wallet, as shown and described.

DESCRIPTION

FIG. 1 is a front elevational view of a wallet, showing my new design;

FIG. 2 is a top plan view thereof;

FIG. 3 is a right side elevational view thereof;

FIG. 4 is a rear elevational view thereof;

FIG. 5 is a bottom plan view thereof;

FIG. 6 is a left elevational view thereof;

FIG. 7 is a front elevational view thereof, showing the wallet in an opened condition;

FIG. 8 is a rear elevational view thereof, showing the wallet in an opened condition;

FIG. 9 is a perspective view thereof, showing the wallet in an opened condition; and,

FIG. 10 is an exploded perspective view thereof.

The broken lines in FIGS. 1, 2, 4, 5, 7, 8, 9 and 10 represent stitching for holding the parts of the case together.
